Primary Examiner — T Chase Nelson(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is a bottom view thereof;

FIG. 5 is a bottom rear perspective view thereof; and,

FIG. 6 is a bottom front perspective view thereof.

The broken line showing of the circular region forms no part of the claimed design. The broken lines depicting the remainder of the shoe form no part of the claimed design.
